[57] CLAIM

The ornamental design for a combined bottle and cap, as
shown and described.

DESCRIPTION

FIG. 1 is a front elevation of a combined bottle and cap showing our new design;

FIG. 2 is a top plan view thereof;

FIG. 3 is a bottom plan view thereof;

FIG. 4 is a front elevation of a second embodiment of the
combined bottle and cap, which is the same as the first
embodiment except for the cap;

FIG. 5 is a top plan view thereof;

FIG. 6 is a bottom plan view thereof;

FIG. 7 is a front elevation of a third embodiment of the
combined bottle and cap which is the same as the first two
embodiments except for the cap;

FIG. 8 is a top plan view thereof; and,

FIG. 9 is a bottom plan view thereof.

The rear and side views of the three embodiments of the
combined bottle and cap are the same as the front views
shown in FIGS. 1, 4 and 7.
